ELECTRIC CIRCUIT BREAKER AND METHOD
OF OPERATING THE SAMEDidier Journeaux, Wauwatosa, Wis., assignor to
Allis-Chalmers Manufacturing Company, Mil-
waukee, Wis., a corporation of Delaware

Application May 16, 1942, Serial No. 443,259

25 Claims. (Cl. 200—148)

This invention relates in general to improvements in electric circuit breakers of the fluid blast type, and more particularly to means and a method of operation for reducing the deterioration of the contacts during opening and closure of the circuit breaker.

Electric circuit breakers of the fluid blast type of high current carrying capacity are frequently provided with arcing contacts for opening the circuit, main contacts for carrying the current when the circuit breaker is closed, and disconnecting contacts for maintaining the circuit open after interruption of the current at the arcing contacts. In such circuit breakers it is advantageous to utilize the pressure of the arc extinguishing fluid to aid in holding the arcing contacts closed while the main contacts are being opened so as to facilitate the transfer of current from the main contacts to the arcing contacts. If the opening movement of the contacts takes place in a direction opposite to the direction of the fluid blast, however, the contact pressure produced by the air blast must be overcome to open the arcing contacts. This disadvantage may be obviated by providing two cooperating movable arcing contacts having different strokes, and opening the contacts by moving both in the direction of the fluid blast. In addition thereto, the admission of fluid under pressure between the cooperating surfaces of the arcing contacts may be delayed until substantially the time of parting of the main contacts to prevent any premature opening action of the fluid on the arcing contacts.

The fluid blast accompanying the opening of the arcing contacts is preferably initiated substantially at the time of opening of the main contacts through a path bypassing the arcing contacts. In this manner the fluid column in the arcing chamber is already set in motion at the time of opening of the arcing contacts with a negligible loss of fluid. To maintain the consumption of fluid at a minimum, the fluid blast should be reduced or even completely stopped as soon as the arc may be assumed to be extinguished. Good operating practice also requires that disconnecting contacts be opened at that time. It is therefore advantageous to utilize the opening movement of the disconnecting contacts to control the reduction of the fluid blast after interruption of the arc.

Reclosure of the circuit breaker is generally effected by first reclosing the arcing contacts and thereafter reclosing the disconnecting contacts. An arc may therefore be momentarily established between the disconnecting contacts while they

5 are approaching their closed position, and the current of the circuit flows through an abnormally small contact area from the first engagement of the disconnecting contacts until the contacts reach their normal closed position. For these reasons the contacts are subject to gradual deterioration. It is therefore advantageous to reopen the arcing contacts prior to closing the disconnecting contacts and to complete the circuit 10 at the arcing contacts, which are designed to operate satisfactorily even when their surfaces have been burned by the arc. The reopening of the arcing contacts may be effected with the usual fluid blast provided for arc interruption. The 15 reopening may also be effected in a blast of reduced intensity or in confined fluid to reduce the consumption of fluid.

It is therefore one of the objects of the present invention to provide an improved circuit breaker of the fluid blast type in which the arcing contacts are held closed by the fluid blast at the 20 time of separation of the main contacts.

Another object of the present invention is to provide an improved circuit breaker of the fluid blast type in which the opening movement of the main and arcing contacts takes place in the direction of flow of the fluid blast.

Another object of the present invention is to provide a circuit breaker of the fluid blast type 25 in which the fluid blast in the arcing zone is set in motion substantially simultaneously with the opening of the main contacts and prior to opening of the arcing contacts.

Another object of the present invention is to provide a circuit breaker of the fluid blast type 30 in which the fluid blast is controlled by disconnecting contacts serially connected with the arcing contacts.

Another object of the present invention is to provide a circuit-breaker of the fluid blast type in which the circuit is closed as well as opened at the arcing contacts and is only held open by means of the disconnecting contacts.

Another object of the present invention is to provide a method of operating a circuit breaker comprising the steps of closing disconnecting contacts prior to closing the arcing contacts associated therewith.

Objects and advantages other than those above set forth will be apparent from the following description when read in connection with the accompanying drawing, in which:

Fig. 1 diagrammatically illustrates, partly in elevation and partly in cross-section, a circuit

breaker of the air blast type embodying the present invention;

Fig. 2 is a diametrical cross-sectional view of the arcing chamber taken through line II-II in Fig. 1 showing the main and arcing contacts in closed position and showing the movable disconnecting contact removed from its actual position to illustrate the control of the fluid blast by the movable disconnecting contact;

Fig. 3 is a fragmentary view of the arcing chamber illustrated in Fig. 2 showing the main and arcing contacts in fully open position;

Fig. 4 is a top view of movable arcing contact of the embodiment illustrated in Fig. 2;

Fig. 5 is a view similar to Fig. 2 of a modified embodiment of the invention taken partly through a plane parallel to the main plane of section to illustrate the external air relays controlling the fluid blast;

Fig. 6 is a fragmentary view of the arcing chamber illustrated in Fig. 5 showing the main and arcing contacts in fully open position; and

Fig. 7 is a top view of the movable arcing contact of the embodiment illustrated in Fig. 5.

Referring more particularly to the drawings by characters of reference, the circuit breaker illustrated in Fig. 1 comprises a reservoir 11 constituting a source of arc extinguishing fluid. The fluid may be an inert gas such as nitrogen, but it will be assumed herein that the fluid is compressed air supplied to the reservoir by a suitable compressor (not shown). The current carrying parts of the circuit breaker are supported on reservoir 11 through a hollow insulator 12 and a post type insulator 13. Insulator 12 supports a short tubular conductive member 14 provided with a terminal 15 for connecting the circuit breaker in an electric circuit 16. Member 14 supports a hollow insulator 17 containing the main and arcing contacts of the circuit breaker. A conductive cylinder 18 cooperates with insulator 17 to define an arcing chamber 19. Cylinder 18 also contains the actuating mechanism for the main and arcing contacts and is divided into a plurality of parts to permit machining of its inner working surfaces to permit introduction therein of the different movable elements associated therewith. A movable disconnecting contact 20 is pivoted on cylinder 18 and is associated with a fixed disconnecting contact 21 mounted on insulator 13 with the second terminal 22 of the circuit breaker.

Insulator 12 provides a connection between reservoir 11 and arcing chamber 19 through a suitable valve 23 for producing a blast of air under pressure between the arcing contacts and through the arcing chamber. Valve 23 may be opened by an air motor 24 of the spring biased reciprocating type. Air under pressure is supplied from reservoir 11 to motor 24 through a magnet valve 26. The coil 27 of valve 26 may be energized from a suitable source, such as a battery 28, through a push button switch 29 and through an auxiliary switch 30 controlled by the circuit breaker. Switch 29 may be connected in parallel with the contacts of a relay 31. The coil of relay 31 may be energized from a current transformer 32 serially connected with the circuit breaker in circuit 16 to render the opening of the circuit breaker responsive to an operating condition of the circuit. Valve 26 may also control a second air motor 33 for actuating a pressure release valve 34 connected with the arcing chamber through insulator 12.

Contact 20 may be opened by means of an

air motor 36 through an insulating rod 31. Motor 36 may be connected with reservoir 11 through magnet valve 26. Contact 20 may be reclosed by means of an air motor 38 through rod 37 and through a rocking lever 39. Motor 38 may be connected with reservoir 11 through a magnet valve 40 having a coil 41. Valve 40 may be integral with a stop valve 45 inserted in the conduit joining valve 26 with motor 36 to prevent simultaneous supply of air under pressure to motor 36 and motor 38. Battery 28 may be connected with coil 41 through a second push button switch 42 and a second auxiliary switch 43. Switch 42 controls a connection between battery 28 and coil 27 through a third auxiliary switch 44. The three auxiliary switches may be jointly actuated from lever 39 through a connecting rod 46 and a crank 47.

As shown in Fig. 2, arcing chamber 19 contains cooperating main contacts 48, 49 and cooperating arcing contacts 50, 51 connected in parallel therewith. The main and arcing contacts are also serially connected with contacts 20, 21 through cylinder 18. Contact 48 is divided into a plurality of segments resiliently mounted on a conductive annular contact holder 52 shaped as a solid of revolution and bolted or cast in the bore of member 14 so as to extend into the bore of insulator 17. Holder 52 is bounded by a plurality of surfaces including a plane surface 53 intersecting a concave surface of revolution 54. The segments of contact 48 are arranged adjacent surface 54 and are urged thereagainst by springs 56 so as to define substantially a convex surface of revolution 57. The cooperating movable main contact 49 is coaxial with holder 52 and is bounded by a plurality of surfaces including a plane surface 58 intersecting a concave surface of revolution 59. Contact 49 is annular and defines an orifice 55. Contacts 48, 49 are preferably maintained in mutual engagement by means of a spring 60.

Contact 49 is mounted on a sleeve 61 adapted to slide into the bore of cylinder 18. An annular piston 62 mounted on sleeve 61 or on contact 49 cooperates with other elements of the circuit breaker to actuate the sleeve for opening contacts 48, 49 under the action of the air pressure within the arcing chamber. Piston 62 is arranged within a sleeve 63 extending downward from cylinder 18. The down stroke of sleeve 61 is limited by engagement of contact 48 with support 52 and the up stroke of the sleeve is limited by engagement of an annular thrust member 64 with a step of sleeve 63. The conduction of current between sleeve 61 and cylinder 18 may be effected through any suitable means such as contact segments 66 arranged in an annular recess 67 of cylinder 18 and urged against the cylinder wall and against sleeve 61 by a garter spring 68.

Contact holder 52 contains the so-called fixed arcing contact 58 which comprises a stem portion 69 guided into a bore of support 52 and carrying a piston 70. The piston is adapted to slide within a short cylinder 71 provided in support 52. Contact 58 is resiliently urged into engagement with the cooperating contact 51 by a spring 72 which is relatively weak compared to spring 60. Current is preferably conducted between contact 50 and support 52 through flexible conductors 73. Contact 50 has a relatively short stroke and its movement is limited by abutment of piston 70 and of the contact itself with

the adjacent portions of contact holder 52. An annular shield 74 interposed between contacts 48 and 50 aids in guiding the air blast between the contacts and shields contact 48 against projection of material separated from contacts 50, 51 by the arc.

The movable arcing contact 51 is a nozzle shaped contact and is provided with short spokes 76 for mounting the contact in mechanical and conductive connection with contact 49 within orifice 55. Contact 51 thus divides the orifice into a central portion and a plurality of segmental slots 77. When contacts 50, 51 are closed, they may be considered as dividing arcing chamber 19 into an inlet chamber 78 having its inlet defined by member 14 and holder 52, and an outlet chamber 79. The outlet chamber extends upward from contact 51 through cylinder 18 to suitable outlet means 80 provided on the cylinder. Slots 77 form a path for the flow of air from the inlet chamber into the outlet chamber independently of the opening of contacts 50, 51. The flow of air through slots 77, however, depends on the position of contact 49 which cooperates with contact holder 52 to form valve means controlling the flow of air through the slots and also controlling the admission of air from the inlet chamber to the engaging surfaces of contacts 50, 51.

Outlet chamber 79 contains a bent electrode 81 extending through the wall of cylinder 18 through an insulating bushing 82 and connected with member 14 through a suitable resistor 83. Electrode 81 is preferably surrounded by a plurality of coaxial metallic baffles 84 connected therewith and serving to cool and deionize the air blast passing through the arcing chamber. An insulating sleeve 86 is inserted within cylinder 18 and sleeve 61 and about electrode 81 and baffles 84 to prevent flashovers therebetween. A shield 87 mounted on sleeve 61 prevents deposition on the lower part of sleeve 86 of material separated from the arcing contacts by the arc.

Baffles 88 may be arranged within passages 85 leading from outlets 80 to atmosphere to assist baffles 84 in cooling the air blast and to prevent accidental introduction of foreign material into the circuit breaker. Check valves 89 may be further provided to prevent circulation of dust or snow laden air from one outlet to the other through the arcing chamber.

Outlets 80 are controlled by suitable valve means such as a balanced poppet valve 90. The valve is normally maintained open by a spring 91 and may be actuated by a piston 92 adapted to slide within a cylinder 93. When valve 90 is closed, the air flow through arcing chamber 19 may be completely interrupted, or additional outlets 94 may be provided to define a path for a reduced blast of air sufficient to maintain the arcing contacts open and to prevent reignition of the arc.

Cylinder 93 may be supplied with air under pressure from inlet chamber 78 through a port 96, an air relay 97 and a conduit 98. The piston 99 of relay 97 is urged toward the right by the air pressure transmitted from the inlet chamber. When contact 20 is closed, movement of piston 99 to admit air under pressure to cylinder 93 is prevented by an adjustable stop 100 provided on contact 20.

In operation, the circuit breaker being closed as shown in Figs. 1 and 2, current flows between terminals 15 and 22 through member 14, contact holder 52, contacts 48, 49 and 50, 51, sleeve 61, contacts 66, cylinder 18, and contacts 20, 21.

The flow of current takes place mostly through the main contacts 48, 49 because of the small area of the cooperating surfaces of arcing contacts 50, 51, of their burning by previously established arcs, and of the relatively low contact pressure afforded by spring 72.

Opening of the circuit breaker may be initiated by closing switch 29 or by operation of relay 31 in response to a flow of current of excessive magnitude through the circuit breaker and through current transformer 32. Battery 18 is thereby connected with coil 27 through switch 30, and the coil actuates valve 26. Air under pressure is admitted from reservoir 11 through valve 26 to motors 24, 33 and 36. The three motors are suitably dimensioned to insure their operation in the desired sequence at the desired time intervals. Motor 33 operates to close valve 34. Motor 24 may operate at the same time as motor 33 or immediately thereafter to open valve 23. Air under pressure is admitted from reservoir 11 through valve 23 into insulator 12, member 14, and inlet chamber 78. Air pressure is thereby applied to the lower faces of pistons 62 and 70, the upper faces of which are subjected to atmospheric pressure. The air pressure on piston 70 cooperates with spring 72 to urge contact 50 against contact 51, thereby holding the contacts closed under a greatly increased pressure, imparting to contacts 49, 50, 51 a joint initial acceleration. The air pressure on piston 62 also accelerates contacts 49, 51 and sleeve 61 without materially lessening the contact pressure of contacts 50, 51 because the inertia of contacts 49, 51 and sleeve 61 is much greater than that of contact 50, stem 69 and piston 70.

Until the contacts begin to move, contact holder 52 and contact 49 cooperate to prevent the access of air from inlet chamber 78 into outlet chamber 79 through slots 77. Air pressure is also thereby withheld from the engaging surfaces of contacts 50, 51 where such pressure would tend to open contacts 50, 51 prematurely in circuit breakers where stem 69 has a greater diameter than the circle along which contacts 50, 51 are in engagement.

Upward movement of the main and arcing contacts first causes contact 49 to disengage contact holder 52. Air under pressure is then admitted to the lower face of contact 49 and assists the upward movement of the contact. Air then may also flow into outlet chamber 79 through slots 77, thereby setting in motion the air column contained within chamber 79 and passages 85 and facilitating the subsequent establishment of a blast therethrough upon opening of contacts 50, 51.

Contact 49 thereafter disengages contact 48, thereby causing the entire flow of current to take place through contacts 50, 51 and conductors 73. This current transfer takes place without difficulty as the high pressure with which contacts 50, 51 are urged against each other causes their contact resistance to be very low.

Upward movement of contact 50 is stopped by abutment of piston 70 against the end wall of cylinder 71. Contact 50 is then in the position shown in Fig. 3 and contacts 48, 49 are then open a predetermined extent. Contacts 49 and 51 thereupon continue their upward movement to open contacts 48, 49 beyond the above mentioned predetermined extent under the action of the impulse imparted thereto by piston 70 and of the continued application of air pressure on the lower faces of piston 62 and of contacts 49,

51. Continued movement of contact 51 causes contact 51 to disengage contact 50. An arc is drawn therebetween and at the same time the air blast initiated through slots 77 is supplemented by the blast through the bore of contact 51. Contacts 49, 51 ultimately reach the fully open position shown in Fig. 3 to establish a gap between contacts 50, 51 of such width as to result in the most efficient arc extinguishing action of the air blast therethrough. It will be observed that the movement of contacts 49, 51 takes place in the direction of the air blast flowing through the nozzle portion of contact 49 so that contacts 50, 51 may be at first held in engagement and thereafter separated without reversal of the application of air pressure to contact 51.

The air blast causes one of the roots of the arc drawn between contacts 50, 51 to travel on contact 50 towards the center of its arc carrying surface. The other root of the arc travels along the bore of contact 51 and is thus always maintained within the contour of the air blast directed through contact 51 and through slots 77 so that no portion of the arc is outside the air blast. The air blast also causes the arc to be looped between the contacts through the bore of contact 51 into chamber 79. The portion of the blast established through slots 77, which is substantially annular, directs the arc toward the axis of chamber 79 and diverts material detached from the arcing contacts by the arc away from shield 81 and sleeve 86. The arc ultimately reaches the tip of electrode 81 and thereupon breaks into two portions. One arc portion extending between contact 50 and electrode 81 is connected in parallel with resistor 83 and extinguishes toward the first half cycle of arcing. The second arc portion extending between contact 51 and electrode 81 is connected in series with resistor 83 and therefore carries a relatively low current at high power factor, so that it is readily extinguished by the air blast. The air blast also prevents reignition of the arc as is well known.

During the above described operation, air under pressure is admitted from chamber 78 and into relay 91, but operation of the relay is initially prevented by stop 100. Air is also admitted from reservoir 11 through valve 26 to motor 36, and the operation of motor 36 is so adjusted that contact 20 disengages contact 21 immediately after the arc drawn between contacts 50, 51 may be assumed to be extinguished. Disengaging movement of contact 20 causes movement of stop 100, thereby enabling the air pressure on the left side of piston 99 to move the piston to the right to connect cylinder 93 with chamber 78. The air pressure on the left side of piston 92 causes the piston to move to the right against the action of spring 91 and valve 90 closes orifices 80.

The flow of air through the circuit breaker is then stopped or continues at a reduced rate through outlets 94 to cause the dielectric strength of the gap between the main and arcing contacts to remain sufficient to prevent reignition of the arc with a minimum consumption of compressed air. When contact 20 reaches its fully open position, the air gap between contacts 20 and 21 is sufficient to maintain circuit 16 open and contacts 48, 49, 50 and 51 may be reclosed. When contact 20 is substantially fully opened, switch 30 disconnects coil 27 from battery 28, and valve 26 recloses. Motor 36 then stops to

5 maintain contact 20 open. Valve 23 is reclosed by the spring of motor 24 and valve 34 is reopened by the spring of motor 33. The arcing chamber is rapidly emptied of air under pressure through valve 34 and the main and arcing contacts are reclosed by spring 60 while valve 93 is opened by spring 91.

10 During return of the main and arcing contacts to the position shown in Fig. 2, the axial movement of contact 49 relative to contact 48 and contact holder 52 causes sequential sliding engagement of contact 49 with the convex surface defined by the segments of contact 48 and abutting engagement of surfaces 53 and 58 to stop contact 49.

15 The circuit breaker may be reclosed by closing switch 42. The switch connects coil 41 with battery 28 through switch 43, which is then closed. Coil 41 actuates valve 40, which admits air under pressure from reservoir 11 to motor 38 to cause the motor to return contact 20 towards the closed position shown. Valve 45 is also actuated to disconnect motor 36 from valve 26. At a predetermined point of the reclosing stroke of contact 20, switch 44 connects battery 28 with coil 27. Coil 27 actuates valve 26, causing valve 34 to close and valve 23 to open to admit air from reservoir 11 to inner chamber 78. Contact 20 then still being open, stop 100 is disengaged from piston 99 and air under pressure is admitted through relay 91 to cylinder 93 to cause immediate closure of valve 90. The air pressure within chamber 78 causes sequential opening of contacts 48, 49 and of contacts 50, 51 in the manner above described. The entire arcing chamber is then filled with air under pressure which is confined within the chamber or allowed to flow at a relatively low rate through orifices 84 so as to hold the contacts open.

20 25 30 35 40 45 50 55 60 65 70 75 Continued movement of contact 20 causes stop 100 to return to the position shown. Upon substantial completion of the closing movement of contact 20, piston 99 is moved by stop 100 to discharge the air contained in cylinder 93 to atmosphere. Spring 91 thereupon returns valve 90 to the open position shown. Substantially at the same time switch 44 opens to disconnect coil 27 from battery 28. Valve 26 returns to the position shown to cause valve 23 to reclose and valve 34 to reopen. Valves 34 and 90 release the air confined within chamber 79, thereby enabling spring 60 to sequentially reclose the arcing contacts and the main contacts. Circuit 16 is reclosed by reengagement of the arcing contacts, but any arcing that may take place between the arcing contacts prior to their reengagement or any local overheating due to insufficient contact area are without detrimental effect as the current is diverted from the arcing contacts as soon as the main contacts close. The circuit breaker thereupon is ready to re-open immediately if the flow of current through circuit 16 is of excessive magnitude.

25 30 35 40 45 50 55 60 65 70 75 In the embodiment illustrated in Fig. 5, the segments of fixed contact 48 are mounted on an annular projection 101 of member 14 instead of on contact holder 52, to engage the convex outer surface of contact 49. An annular shield 102 is mounted on sleeve 44 between the arcing surfaces of contacts 50, 51 and the engaging surfaces of contacts 48, 49 to prevent deposition on the main contacts of material separated from the arcing contacts by the arc.

The bore of contact 51 is provided with a plurality of longitudinal ribs 103, the lower ends of

which abut against contact 50 when the contacts are closed. Ribs 103 form a plurality of alternate paths for the travel of one root of the arc within the contour of the air blast.

In the present embodiment contact 50 is generally disengaged from contact 51 under the action of gravity and of a spring 104. Stem 69 projects through piston 70 and is attached to the hollow stem 106 of a poppet valve 107 having its seat at the lower end of member 14. Valve stem 106 is guided in a sleeve 108 integral with a suitably shaped cylinder head 109 mounted on cylinder 71. Stem 106 is provided with ports 110 cooperating with ports 111 of sleeve 108 to control the admission of air into cylinder 71. The air pressure within cylinder 71 may further be controlled by a pressure responsive valve 112 of any suitable type acting with an adjustable time delay. Valve 112 may comprise a piston 113 subjected to the action of the pressure within cylinder 71 through a needle valve 114. Piston 113 acts against a spring 116 to cause a second piston 117 to connect cylinder 71 with atmosphere.

Valve 90 consists of a pair of unbalanced butterfly members which are interlinked through a pair of cranks 118 and a connecting rod 119. The valve members are so disposed within outlets 80 as to be closed by the air blast through the outlets and are otherwise maintained open by spring 91 in a position determined by abutment of a crank 118 with a stop 120. The closure of valve 90 is controlled by latch 121 actuated by an air motor 125 connected with the arcing chamber through conduit 98, relay 97 and port 96. Relay 97 is provided with a second piston 122 controlling a conduit 123. The position of the pistons is controlled by stop 100 and by a spring 124.

Conduit 98 is controlled by a second air relay 126 similar to relay 97 and comprising a piston 127 subjected to the pressure of the arcing chamber through relay 97 and conduit 123, a piston 128 controlling conduit 98, and a spring 129.

The operation of the present embodiment is generally similar to that of the embodiment illustrated in Fig. 2 except as hereinafter specifically set forth.

When the circuit breaker is to be opened, valve 23 is caused to open as above described. Valve 107 being initially closed, the air pressure is momentarily withheld from contacts 49, 51 and piston 62. The air pressure acts on the lower face of valve 107 and, through stem 106 and ports 110, 111, on the lower face of piston 70. The air pressure thus applied causes impact of contact 50 against contact 51 to impart an initial acceleration thereto and to hold the contacts closed under high pressure until opening of the main contacts. Valve 107 also opens to admit air under pressure to the lower face of contact 51 and to shield 102 to assist in moving sleeve 61 with contacts 49, 51 and to cause opening of contacts 48, 49. Movement of contact 49 admits air under pressure through slots 77 into chamber 79. Air is also admitted to the lower face of piston 62 to complete the movement of the contacts and to cause opening of contacts 50, 51 against the action of spring 60. The air blast established between the contacts extinguishes the arc as above described.

Upon opening movement of contact 49, air under pressure is admitted from the arcing chamber through port 96, relay 97 and conduit 123 to the left side of piston 127. Piston 127 moves piston 128 to the right against the action of

spring 129. Upon opening movement of contact 20, spring 124 moves pistons 122 and 99 to the right at a rate determined by the movement of stop 100. Piston 122 closes conduit 123 and piston 99 substantially simultaneously therewith connects conduit 98 with port 96. Air under pressure is then admitted from the arcing chamber to motor 125 through port 96, relay 97, conduit 98 and relay 126. Latch 121 is withdrawn by the motor to release valve 90, which is closed by the blast then established through outlets 80. Upon further opening of contact 20, piston 122 connects conduit 123 with atmosphere, and spring 129 returns pistons 127, 128 to the position shown. Motor 125 is thereby connected to atmosphere and returns latch 121 to the position shown.

When valve 23 is reclosed and valve 34 is reopened, the release of the air pressure from arcing chamber 19 enables valve 90 to return to the open position shown and to reengage latch 121. Contacts 49, 51 are moved downward by spring 60 until engagement of contact 51 with contact 50. At that moment air under pressure is confined within the cylinder 71 because ports 110 are out of registration with ports 111 when contact 50 is at the top of its stroke. At first the air pressure within cylinder 71 holds contact 50 in its top position and prevents reclosure of contacts 48, 49. Air under pressure is, however, admitted slowly from cylinder 71 through valve 114 to the right side of piston 113. After a predetermined time delay the air pressure on piston 113 overcomes the action of spring 116 and causes pistons 113, 117 to move to the left. Piston 117 connects cylinder 71 with atmosphere to enable contacts 49, 50 and 51 to return to the position shown in Fig. 5.

When the circuit breaker is to be reclosed, air under pressure is admitted first to motor 26 and afterwards momentarily to motors 24, 33 in the manner above described. Air under pressure is then again admitted to the arcing chamber to cause contacts 48, 49, 50 and 51 to open before contact 20 closes. While contact 20 is still open, piston 122 connects conduit 123 to atmosphere and relay 126 remains in the position shown. Air under pressure is not admitted to motor 125 and valve 90 is held open by latch 121.

During completion of the closing movement of contact 20, pistons 99, 123 are gradually returned by stop 100 to the position shown. Piston 99 first disconnects conduit 98 from port 96 and piston 122 thereafter connects conduit 123 with port 96. Pistons 127, 128 are thereby caused to move to the right as above described, but the connection between motor 125 and the arcing chamber remains interrupted by piston 99 so that latch 121 is not withdrawn. Substantially at the time of full closure of contact 20, valve 23 recloses and the arcing chamber is returned to atmospheric pressure. Contacts 50, 51 immediately reclose as above described. Because of the action of time delay relay 112 contacts 48, 49 remain disengaged for a predetermined length of time after reclosure of the arcing contacts. The flow of current through circuit 16 is reestablished upon reclosure of the arcing contacts, and if this current is of excessive magnitude, the circuit breaker immediately reopens in the manner above described. In the interval between reclosure and reopening of the circuit breaker the excessively high current is carried only by the arcing contacts, thereby reducing the danger of damage to the main contacts.

Although but two embodiments of the present

invention have been illustrated and described, it will be apparent to those skilled in the art that various modifications and changes may be made therein without departing from the spirit of the invention or from the scope of the appended claims.

It is claimed and desired to secure by Letters Patent:

1. An electric circuit breaker comprising cooperating arcing contacts, cooperating main contacts connected in parallel with said arcing contacts, means operable by fluid under pressure acting on one of said arcing contacts for simultaneously actuating said arcing contacts and one of said main contacts to maintain said arcing contacts closed under pressure while opening said main contacts a predetermined extent, and means operable by fluid under pressure for continuing the action of the other one of said arcing contacts and of said one of said main contacts for opening said arcing contacts and for opening said main contacts beyond said predetermined extent.

2. An electric circuit breaker comprising cooperating stationary and movable main contacts, an arcing contact connected with said stationary main contact and mounted in said circuit breaker for movement within predetermined limits, a movable arcing contact in mechanical and conductive connection with said movable main contact, means operable by fluid under pressure for actuating said movable main and arcing contacts for opening said main contacts and for thereafter opening said arcing contacts, and means actuated by fluid pressure acting on the first said arcing contact within said limits for cooperating with the first said means in actuating said movable main and arcing contacts and maintaining said arcing contacts closed under pressure until separation of said main contacts.

3. An electric circuit breaker comprising cooperating stationary and movable main contacts, an arcing contact connected with said stationary main contact and mounted in said circuit breaker for movement within predetermined limits, a movable arcing contact in mechanical and conductive connection with said movable main contact, resilient means urging the first said arcing contact into engagement with said movable arcing contact during movement of the first said arcing contact within said predetermined limits, means operable by fluid under pressure acting on said main and arcing movable contacts for opening said main contacts and for thereafter opening said arcing contacts, and means operable by fluid under pressure acting on the first said arcing contact during operation of the first said means for increasing the contact pressure of said arcing contacts from the beginning of the opening operation of said main contacts until separation of said arcing contacts.

4. An electric circuit breaker comprising cooperating stationary and movable main contacts, a movable arcing contact in mechanical and conductive connection with said movable main contact, an arcing contact mounted in the circuit breaker for limited movement causing said arcing contacts to open when said main contacts are closed, means operable by fluid under pressure acting on the second said arcing contact to cause impact of the second said arcing contact on said movable arcing contact to actuate said movable main and arcing contacts and cause separation of said main contacts with transfer of the current from said main contacts to said arcing contacts, and means operable by fluid under pressure

for further actuating said movable contacts to open said arcing contacts.

5. An electric circuit breaker comprising an arcing chamber, a pair of cooperating arcing contacts arranged in said chamber, cooperating fixed and movable main contacts arranged in said chamber and connected in parallel with said arcing contacts, means for directing a blast of arc extinguishing fluid through said chamber, and means for sequentially opening said main and arcing contacts comprising means operable by fluid under pressure for moving one of said arcing contacts in the direction of said blast a predetermined extent, and means distinct from the first said contact moving means operable by fluid under pressure for moving the other one of said arcing contacts and said movable main contact in the direction of said blast an extent greater than said predetermined extent.

10 6. In combination, an electric circuit, a circuit breaker comprising cooperating arcing contacts, cooperating disconnecting contacts serially connected with said arcing contacts in said circuit, main contacts connected in parallel with said arcing contacts, means for causing opening of said main and arcing contacts comprising means operable by fluid under pressure for simultaneously actuating said arcing contacts and one of said main contacts to impart a joint initial acceleration thereto, means operable by fluid under pressure for continuing the actuation of only one of said arcing contacts and of said one of said main contacts to cause sequential opening of said main contacts and of said arcing contacts, means operable by fluid under pressure for opening said disconnecting contacts while said arcing contacts are open, and means comprising a source of fluid under pressure for controlling the operation of said contact opening means.

40 7. An electric circuit breaker comprising an arcing chamber having an inlet, a pair of cooperating arcing contacts arranged to divide said chamber into an inlet portion and an outlet portion, a pair of cooperating main contacts connected in parallel with said arcing contacts, means for introducing arc extinguishing fluid under pressure into said chamber through said inlet, means for opening said main contacts and for admitting said fluid from said inlet to the engaging surfaces of said arcing contacts, and means for opening said arcing contacts to draw an arc therebetween and to thereby establish a path for a blast of said fluid from said inlet portion to said outlet portion between said contacts to extinguish the arc.

45 8. An electric circuit breaker comprising an arcing chamber having an inlet and an outlet, a pair of cooperating arcing contacts arranged to divide said chamber into an inlet portion and an outlet portion, a pair of cooperating main contacts connected in parallel with said arcing contacts, means for introducing arc extinguishing fluid under pressure into said inlet portion, means forming a path for the flow of said fluid from said inlet portion into said outlet portion independently of opening of said arcing contacts, valve means comprising one of said main contacts for controlling said path, and common means for sequentially opening said valve means to initiate the flow of said fluid from said inlet portion into said outlet portion, opening said main contacts, and opening said arcing contacts to draw an arc therebetween and to thereby establish a path for a blast of said fluid from said inlet portion to said outlet portion between said contacts to extinguish the arc.

9. An electric circuit breaker comprising an arcing chamber having an inlet and an outlet, a pair of cooperating arcing contacts arranged to divide said chamber into an inlet portion and an outlet portion, means for introducing arc extinguishing fluid under pressure into said inlet portion, means forming a path for the flow of said fluid from said inlet portion into said outlet portion, a first valve means for controlling said path, a second valve means for controlling said outlet, means for opening said first valve means to initiate the flow of said fluid from said inlet portion into said outlet portion, means for thereafter opening said contacts to draw an arc therebetween and to cause a blast of said fluid between said contacts to extinguish the arc, and means for causing operation of the second said valve means after extinction of the arc to reduce the blast of fluid between said contacts and maintain said chamber under pressure to prevent reignition of the arc.

10. An electric circuit breaker comprising a pair of cooperating arcing contacts, cooperating stationary and movable main contacts connected in parallel with said arcing contacts, means for opening said main contacts and for thereafter opening said arcing contacts to draw an arc therebetween, means for directing a blast of arc extinguishing fluid between said main and arcing contacts to extinguish the arc, and a shield unitary with said movable main contact and interposed between said main contacts and said arcing contacts to prevent deposition on said main contacts of material separated from said arcing contacts by the arc.

11. An electric circuit breaker comprising an annular conductive member bounded by a plane surface intersecting a concave surface of revolution, a plurality of contact segments arranged adjacent said concave surface of revolution to define substantially a convex surface of revolution, means for resiliently mounting said contacts on said member and for urging said segments against said concave surface of revolution, a contact coaxial with said member bounded by a second plane surface intersecting a second concave surface of revolution, and means for causing relative axial movement of said member and of said contact to cause sequential sliding engagement of said contact with the convex surface of said segments and abutting engagement of said plane surfaces.

12. An electric circuit breaker comprising cooperating arcing contacts, cooperating main contacts connected in parallel with said arcing contacts, a source of arc extinguishing fluid under pressure, means operable by fluid under pressure for opening said main contacts, means operable by fluid under pressure for opening said arcing contacts, and means responsive to the operation of the second said contact opening means for controlling the supply of fluid from said source to the first said contact opening means.

13. An electric circuit breaker comprising an arcing chamber having an outlet, a pair of cooperating arcing contacts arranged in said chamber, means for opening said contacts, means for producing a blast of arc extinguishing fluid directed between said contacts and through said chamber, valve means for controlling said outlet, a pair of cooperating disconnecting contacts serially connected with said arcing contacts, one of said disconnecting contacts being movable, and means responsive to movement of said mov-

able disconnecting contact for controlling the operation of said valve means.

14. An electric circuit breaker comprising an arcing chamber having an outlet, a pair of cooperating arcing contacts arranged in said chamber, means for opening said contacts, means for producing a blast of arc extinguishing fluid directed between said contacts and through said chamber, valve means for controlling said outlet, a pair of cooperating disconnecting contacts serially connected with said arcing contacts, means for opening said disconnecting contacts, and means responsive to the operation of said disconnecting contact opening means for causing operation of said valve means.

15. An electric circuit breaker comprising an arcing chamber having an outlet, a pair of cooperating arcing contacts arranged in said chamber, means for opening said contacts, means for producing a blast of arc extinguishing fluid directed between said contacts and through said chamber, valve means for controlling said outlet, a pair of cooperating disconnecting contacts serially connected with said arcing contacts, means for opening said disconnecting contacts, means operable by fluid under pressure for closing said valve means, and means responsive to opening of said disconnecting contacts for connecting said valve closing means with said arcing chamber.

16. An electric circuit breaker comprising an arcing chamber having an outlet, a pair of cooperating arcing contacts arranged in said chamber, means for opening said contacts, means for producing a blast of arc extinguishing fluid directed between said contacts and through said chamber, valve means for controlling said outlet, a pair of cooperating disconnecting contacts serially connected with said arcing contacts, means for opening said disconnecting contacts, means operable by fluid under pressure from said chamber for closing said valve means, and means responsive to pressure within said chamber and to opening of said disconnecting contacts for controlling the operation of said valve closing means.

17. An electric circuit breaker comprising an arcing chamber, a pair of cooperating arcing contacts arranged in said chamber, a pair of cooperating disconnecting contacts serially connected with said arcing contacts, means for closing said disconnecting contacts, means responsive to closing movement of said disconnecting contacts for filling said chamber with arc extinguishing fluid under pressure and for opening said arcing contacts, and means responsive to substantial completion of the closing movement of said disconnecting contacts for releasing the fluid contained within said chamber and for reclosing said arcing contacts.

18. An electric circuit breaker comprising an arcing chamber, a pair of cooperating arcing contacts arranged in said chamber, a pair of cooperating disconnecting contacts serially connected with said arcing contacts, means for closing said disconnecting contacts, means responsive to closing movement of said disconnecting contacts for opening said arcing contacts and for directing a blast of arc extinguishing fluid between said contacts and through said chamber, and means responsive to substantial completion of the closing movement of said disconnecting contacts for reclosing said arcing contacts and interrupting said fluid blast.

19. An electric circuit breaker comprising an

arcng chamber, a pair of cooperating arcng contacts arranged in said chamber, one of said contacts being an annular contact, means for opening said contacts to draw an arc therebetween, means for directing a blast of arc extinguishing fluid through said chamber, between said contacts and through said annular contact, said annular contact comprising a nozzle shaped portion forming a path for one of the roots of the arc wholly within the contour of said blast.

20. An electric circuit breaker comprising a pair of cooperating arcng contacts, a pair of cooperating disconnecting contacts serially connected with said arcng contacts, means for opening said arcng contacts, means for closing said disconnecting contacts, means for reclosing said arcng contacts, and means for causing sequential operation of the first, second and third said means in the order recited.

21. The method of effecting a normal circuit closing operation of a circuit breaker comprising arcng contacts serially connected with disconnecting contacts in the circuit comprising the steps of opening the arcng contacts, closing the disconnecting contacts, and reclosing the arcng contacts to complete the circuit.

22. An electric circuit breaker comprising a pair of cooperating arcng contacts, a pair of cooperating main contacts connected in parallel with said arcng contacts, a pair of disconnecting contacts serially connected with said arcng and main contacts, means for opening said main contacts, means for opening said arcng contacts, means for closing said disconnecting contacts, means for reclosing said arcng contacts, and means for reclosing said main contacts, and

means for causing sequential operation of the different said means in the order recited.

23. The method of closing an electric circuit comprising the steps of opening a pair of main contacts connected in the circuit, opening a pair of arcng contacts connected in parallel with the main contacts, closing a pair of disconnecting contacts serially connected with the main and arcng contacts, reclosing the arcng contacts and reclosing the main contacts.

24. An electric circuit breaker comprising a pair of cooperating arcng contacts, a pair of cooperating main contacts connected in parallel with said arcng contacts, means for opening said main and arcng contacts, means for reclosing said arcng contacts, and time delay means for reclosing said main contacts after reclosure of said arcng contacts.

25. An electric circuit breaker comprising a pair of cooperating arcng contacts, a pair of cooperating main contacts connected in parallel with said arcng contacts, a source of arc extinguishing fluid under pressure, a nozzle unitary with one of said main contacts, said nozzle being closed by one of said arcng contacts when said arcng contacts are closed, means for causing movement of one of said main contacts and one of said arcng contacts to open said main contacts and thereafter to open said arcng contacts to draw an arc therebetween, said contacts defining a path for the flow of fluid from said source through said nozzle to extinguish the arc, the said movements of said contacts being in the direction of the said flow of fluid through said nozzle.

DIDIER JOURNEAUX.
